United States Patent

Des. 239,312
Patented Mar. 23, 1976

239,312

RING

William L. Foreman, 123 Las Vegas,
Orinda, Calif. 94563

Filed Dec. 6, 1974, Ser. No. 530,327

Term of patent 14 years

Int. Cl. D11—01

U.S. Cl. D45—10 A

FIG _ 1

FIG - 2

FIG - 4

FIG - 3

FIG - 5

FIG - 6

FIG. 1 is a perspective view of a ring showing my new design;

FIG. 2 is a top plan view of the ring;

FIG. 3 is a front elevational view;

FIG. 4 is a left end elevational view;

FIG. 5 is a right end elevational view; and

FIG. 6 is a bottom plan view.

FIGS. 2-6 are drawn to a reduced scale relative to the scale of FIG. 1.

I claim:

The ornamental design for a ring, as shown.
